CARD FOR LOOSE-LEAF-INDEX DEVICES.

1,194,387.

Specification of Letters Patent. Patented Aug. 15, 1916.

Application filed December 30, 1911. Serial No. 668,728.

To all whom it may concern:

Be it known that I, GARRETT H. HUISING, a citizen of the United States, residing in Chicago, county of Cook, and State of Illinois, have invented a certain new and useful Improvement in Cards for Loose-Leaf-Index Devices, of which the following is a specification.

My invention relates to that class of card indexes in which a card or group of cards is displaced from the normal plane of the remainder by any suitable mechanism. Numerous devices of this kind have been invented, but all with which I am familiar are 15 inoperative due to the fact that the friction existing between the surfaces of the cards is so great that when the mechanism is operated for the purpose of elevating a single card, it will carry up not only that card but 20 always the cards adjacent to it, while in many instances as many as a dozen cards are carried up by the elevation of a single card. This is due not only to the friction existing between the surfaces of the cards, but is frequently caused by the engagement of the pin or clip which forms the connection between the card and the elevating mechanism engaging the next adjacent card.

In most card indexes of this character it 30 is deemed necessary to provide a resting place for the cards, so as to prevent their resting upon the pins themselves. This is generally done by having a shoulder near the bottom of the side walls of the box upon 35 which the cards may rest. Practice has shown, however, that in a comparatively short time the constant replacing of the cards breaks the edges or corners of them down to such an extent that they will slip 40 off of the shoulder thus formed and become wedged so that when the user desires to elevate the card, which had wedged itself in this way, he finds it impossible to do so.

My invention has for its object to provide 45 means for overcoming all of these objections and produce a card having protectors secured to its ends, which will insure the rise of a single card without reference to the number of cards which are in the box.

50 My means of accomplishing the foregoing may be more readily understood by having reference to the accompanying drawings, which are hereunto annexed and are a part of this specification, in which:

55 Figure 1 is a top or plan view of a frag-

mentary portion of a card index box, employing cards provided with my improvement. Fig. 2 is a side elevation of the same, a portion of the outer wall being broken away to show the interior construction. 60 Fig. 3 is an enlarged detail view of the top of one of the cards. Fig. 4 is a front view of the same. Fig. 5 is an enlarged perspective view of one of the protectors.

Similar reference numerals refer to similar parts throughout the entire description.

As shown in the drawings, 1 is the box which is provided with a plurality of cards 2, the corners of which rest upon shoulders 3 and 4 formed near the bottom of the side walls 5 and 6. A plurality of longitudinally movable bars 7 are located in the bottom of the box being connected by means of toggles 8 to rising bars 10. The front end of each of the longitudinally movable bars extends 75 upwardly and is secured to a rod 11, which is slidably mounted in the front wall of the box, the outer end of the rod being provided with a key or indicator button 12, upon which may be marked or engraved the desired numeral, letter or character. A plurality of pins or clips 13 which connect the rising bars or card displacers to the cards are secured to the latter in positions which will register with the desired rising bars 10. 80

85 My protectors 14 are shown on the ends of the cards 2 as clearly seen in Figs. 3 and 4 and comprise a fold of tin or other material, which will furnish a satisfactory bearing surface. The protectors 14 are secured to 90 the ends of the cards, and the tin of which they are formed being of the same thickness as the pins 13, effectually precludes their engaging the adjacent cards in any manner whatever. They also serve to space the 95 cards apart so that there is no contact between adjacent surfaces, the only contact being at the edges where the metal strip engages the next adjacent strip. This construction also insures against the danger of 100 the corners of the cards being worn in use, and as a result of such wear dropping off of the shoulders, which form their resting place, and in this manner rendering the device inoperative.

105 Although I have described the reinforcement as being formed of tin, I do not wish to limit myself to that material, as other substitutes may be found in practice, which serve equally well, the essential feature be-

ing that the material used shall be sufficiently thick to clear the pins on adjacent cards, and which furnish a satisfactory bearing surface it may be found desirable 5 in practice to have the tin only extend partially along the edges instead of entirely along them.

Having described my invention what I 10 regard as new and desire to secure by Letters Patent is:

1. The combination with a loose leaf card index, provided with mechanism adapted to elevate a predetermined card or group of cards above their normal position, and comprising connectors secured to the bottom of the cards and adjustable longitudinally thereof, of a plurality of loose leaf cards, the ends of which are provided with a metal binding, the length of which corresponds to 20 the height of the card, said binding being formed of material which forms a suitable bearing surface upon which the next adjacent protector slides when being elevated.

2. The combination with a casing and a 25 plurality of bars therein adapted to elevate a card or group of cards above their normal position, of a plurality of cards each having a binding of metal secured to the ends, and concealed connectors detachably secured to the lower edges of said cards and adjustable longitudinally thereof.

3. The combination with a casing having 30 mechanism for elevating a single card or group of cards above their normal position and a plurality of loose leaf cards, of pro-

tectors on the ends of said cards whereby they are spaced apart, means to effect operative union between the cards and the elevating mechanism, said means being detachably secured to the lower edge of the card and adjustable longitudinally thereof. 40

4. The combination with a casing having mechanism therein for elevating a single card or group of cards above their normal 45 position and a plurality of cards in said casing, a protector secured to each of the ends of the cards which engage the side walls of the casing, said protector being formed of material which is stiffer than the 50 cards and adapted to form bearing surfaces on the sides thereof, a plurality of pins detachably secured to said cards, which engage the elevating mechanism.

5. The combination with a casing having 55 mechanism for elevating a single card or group of cards above their normal position and a plurality of loose leaf cards, a plurality of pins which engage the elevating mechanism detachably secured to the lower 60 edge of the cards, protectors on the ends of said cards whereby they are spaced apart, said protectors being formed of material which forms a suitable bearing surface upon which the cards slide when being elevated. 65

In testimony whereof I have signed the foregoing specification.

GARRETT H. HUISING.
